APPARATUS FOR MANUFACTURE OF SPIRAL SHELLS FOR CONCRETE PILES

Thomas L. Hughes, Youngstown, Ohio, and Albert E. Twist, Jr., Rutherford, N. J., assignors to Raymond Concrete Pile Company, New York, N. Y., a corporation of New Jersey

Application November 7, 1931. Serial No. 573,534

7 Claims. (Cl. 153—2)

This invention pertains to the manufacture of shells for concrete piles, especially shells of the tapered "spiral" type in which the shell is formed with a helical groove in which is tightly wound 5 a stiffening wire.

In the manufacture of such shells it is customary to first wind the wire on a collapsible slightly tapered mandrel, then to place an ungrooved shell on the mandrel outside the wire, 10 then to apply a forming tool to groove the shell around the wire, and finally to collapse the mandrel and remove the shell, which then is spirally grooved with the reinforcing wire in the groove.

It has been found in practice that application 15 of the forming tool tends to stretch the thin metal of the shell, so that after the grooving operation is completed the groove in the shell does not engage the reinforcing wire as tightly as desired. An object of the present invention is to disclose a 20 snubbing device adapted to hold the shell against rotation so that the mandrel and reinforcing wire may be screwed tightly into the grooved shell before removing the shell from the mandrel.

Further and other objects and advantages will 25 be apparent from the specification and claims, and from the accompanying drawings which illustrate what is now considered the preferred embodiment of the invention.

Fig. 1 is a front view of the machine just as 30 the forming tool is completing the grooving of a shell.

Fig. 2 is an enlarged fragmentary view of the grooved shell with wire in place and with grooving roller in forming position.

Fig. 3 is a view of the machine viewed from 35 the right of Fig. 1.

Fig. 4 is a detail view on line 4—4 of Fig. 3 showing counterweight and air cylinder.

Fig. 5 is an enlarged section on line 5—5 of 40 Fig. 1, showing the air control system.

Fig. 6 is a view on line 6—6 of Fig. 5.

Fig. 7 is a cross-section on line 7—7 of Fig. 6.

Fig. 8 is a section through the air control valve.

Fig. 9 is a view of the air valve on line 9—9 of 45 Fig. 8.

Referring to Figs. 1 and 3, the machine has a hollow base 20 upon which is supported for rotation a chuck 22 having slides 24, each slide supporting a leaf 26 of the vertical mandrel 28 which 50 is collapsible by movement of slides 24. The upper end of the mandrel is supported for rotation by a bearing 30 on shaft 32 passing through tail stock 34, and vertically movable therethrough under control of air cylinder 36. The tail stock is 55 pivoted at 38 on frame 40 so that it may be swung

to one side to permit placing a shell on, or removing a shell from, the mandrel. The free end 42 of the tail stock is secured to frame 40 in bracket 44 when in operative position. Frame 40 is supported by parallel cylindrical columns 46 resting 60 on base 20.

Also resting on base 20 are two substantially vertical beams 48 having guide ways 50 on which are slideable carriages 52 and 54 supporting the wire winding roller 56 and grooving roller 58 respectively. Shafts 60 passing upwardly through beams 48 serve to move the carriages along their guides. Beams 48 are adjustable at their upper ends to positions parallel with the tapered sides of the mandrel. Power is supplied 70 to the machine by shaft 62 and distributed by suitable gears within or above base 20 so as to drive the parts of the machine in synchronism.

In operation, with the mandrel expanded, one end of the reinforcing wire 64 (Fig. 2) is fastened by a clamp (not shown) at the upper end of the mandrel and is then tightly wound helically downwardly around the rotating mandrel by winding roller 56 on carriage 52 actuated by a shaft 60. When the lower end of the mandrel is reached, the lower end of the wire is also clamped to the mandrel, and the winding roller, by means of lever 66 is moved to inoperative position. While roller 56 is moving downwardly, grooving roll 58 is being moved upwardly by its carriage 54, so that when the wire winding operation is finished, roller 56 is at the bottom of the mandrel and roller 58 at the top, retracted, however, by mechanism not shown, to inoperative position away from the mandrel.

After the wire is wound on the mandrel, bearing 30 is raised, tail stock 34 is swung to one side, an ungrooved shell 68 is dropped onto the mandrel surrounding the wire, and tail stock 34 and bearing 30 are replaced in their operative positions. Then grooving roller 58 is placed against the shell and drawn downwardly while mandrel and shell are rotating, to groove the shell around the wire, as is best shown at 70 in Fig. 2. The grooving roll is then retracted from contact with the shell and the shell would then be ready for removal from the mandrel were it not for the fact that the grooving operation stretched the metal of the shell so that the shell may not grip the reinforcing wire as tightly as it should. The present invention, which will now be described, is designed to correct that condition.

Mounted on the lower ends of columns 46 is a vertically movable frame 72, made for convenience 110

in two parts fastened together by studs 74. Rollers 76 serve as contact members between frame 72 and columns 46. Passing horizontally through the frame 72 is a lever 78, pivoted on vertical bolt 80 passing through slots 82 and 84 and locked in operative position therein by head 86 and nut 88. The pivot bolt 80 may be locked in various positions, (as for instance those marked 1, 2, 3, 4 and 5 in Fig. 5) to accommodate levers 10 78 of the different lengths necessary for shells of different diameters, which may vary as indicated by the full and dotted lines of Fig. 5.

Pivotedly mounted at 89 on a bracket 90 at one corner of frame 72 is an air cylinder 92, 15 the plunger in which is connected by piston rod 94 at 96 to one end of lever 78. The other end of lever 78 is connected at 98 to one end of a snubber band 100 which passes around the mandrel and shell thereon, to be anchored at its 20 other end at 102 on frame 72. The snubber band is faced with suitable friction material 104.

The weight of frame 72 and its attached parts is counter balanced by a counter weight 106, connection being made between weight and frame 25 by a cable 108 passing over a sheave 110 and attached to frame 72 by a yoke 112. Weight 106 somewhat overbalances the parts at the other end of the cable, and consequently rests constantly on the adjustable fitting 114 on the upper end 30 of piston rod 116 projecting upwardly from plunger 118 in vertical air cylinder 120 bolted to the side of base 20. A rod 122 passing vertically through weight 106 serves to guide the movement of the weight.

35 An air control valve 124 having an operating lever 126 is supported on one of the guide beams 48. The piping from the valve to the operating cylinders will be understood from the somewhat diagrammatic illustration in Fig. 5. Air enters 40 the valve through pipe or hose 128 entering inlet 130, and exhausts from opening 132. Pipe or hose 134 connects opening 136 of the valve to the inner end of cylinder 92, while hose or pipes 138 and 140 connect opening 142 of the valve and 45 pipe 143 simultaneously to the outer end of cylinder 92 and to the lower end of cylinder 120. Pipes 134 and 143 serve to support the valve on beam 48 through the instrumentality of clamps 144. The rotary member of the valve, 50 under control of lever 126 is disc 146, which in its various positions serves to distribute the air through the valve for the purposes of the present invention.

55 After the grooving operation above described is completed, rotation of the mandrel is stopped and valve lever 126 is moved to admit air to pipes 138 and 140 whereby the plunger in cylinder 92, operating on the end of lever 78 to which it is attached at 96, rotates lever 78 counter clockwise 60 about its fulcrum 80, while air through pipe 140 enters the lower end of cylinder 120 to push upwardly on counter weight 106. The movement of lever 78 tightens band 100 around shell 68. The mandrel is then rotated in proper direction 65 to screw the helical wire (which is fast to the tapered mandrel), into the tapered shell until it is tight. During this screwing operation the shell is snubbed, or prevented from turning, by brake band 100, and at the same time the shell, 70 brake band, and frame 72 are all drawn downwardly, plunger 118 assisting in the downward movement by pushing upwardly on counter weight 106.

75 After the screwing down operation is finished, valve lever 126 is moved to exhaust air from pipes

138 and 140 and to admit air through pipe 134 to the inner end of cylinder 92, thus forcing the plunger in cylinder 92 and lever 78 to their normal positions as in Fig. 5, with the snubber band out of contact with the shell. The air being exhausted from below plunger 140 permits weight 106 to restore frame 72 and the snubber to their normal elevated positions as in Fig. 3.

The ends of wire 64 are then released from the mandrel, the mandrel is collapsed, and the spirally grooved, wire-reinforced shell is then lifted off the mandrel, tail stock 34 being, of course, shifted as previously described, to permit its removal.

It is to be understood that the invention is not limited to the specific embodiment herein illustrated and described, but may be used in other ways without departure from its spirit as defined by the following claims.

1. In a machine of the class described, a mandrel adapted to fit within a thin metal shell and means for rotating said mandrel and shell, in combination with a snubber band supported around said shell and operable at the will of the operator for gripping said shell whereby rotation of said shell is prevented while rotation of said mandrel continues. 95

2. In a machine of the class described, in combination, a mandrel having a helical screw thread thereon and adapted to have a shell screwed thereon, means for rotating said mandrel, a snubber band and a support on the machine for gripping said shell to prevent rotation thereof while said mandrel is rotating, whereby said shell and band will travel longitudinally of the mandrel. 110

3. The invention set forth in claim 2 in which said mandrel and shell are tapered, whereby rotation of said mandrel relatively to said shell may tighten said shell on said mandrel. 115

4. In a machine of the class described, in combination, a tapered mandrel having a wire wound helically on the surface of said mandrel, and adapted to receive a shell having a helical groove threaded onto said helically wound wire, means for rotating said mandrel and shell, a snubbing band and a support on the machine adapted for temporarily preventing rotation of said shell with said mandrel, whereby said wire may be screwed more tightly into said helical groove. 125

5. In a machine of the class described, a mandrel adapted to fit within a thin metal shell and means for rotating said mandrel and shell, in combination with a snubber band around the shell, fluid operated means for causing said band to engage or disengage the shell, and means for controlling said fluid operated means. 130

6. In a machine of the class described, in combination, a mandrel having a helical screw thread thereon and adapted to have a shell screwed thereon, means for rotating said mandrel, a snubber band around the shell, fluid operated means for causing said band to engage said shell to prevent rotation thereof while said mandrel is rotating, whereby said shell will travel longitudinally of said mandrel, means for permitting said band to travel longitudinally with said shell, and means for simultaneously controlling said fluid operating means and said permitting means. 135

7. In a machine of the class described, in combination, a vertical tapered mandrel having a helical screw thread thereon and adapted to have a thin metal threaded shell screwed thereon, means for rotating said mandrel, a snubber band around the shell while said shell is on said man- 140

drel, fluid operated means for causing said band to grip said shell to prevent rotation thereof while said mandrel is rotating, whereby said shell will travel downwardly on said mandrel, means for supporting said band whereby said band can move downwardly with said shell, a counterbalance weight for said band supporting means, a

fluid operated plunger for pushing upwardly on said counterweight, and a single means for controlling said plunger and the fluid operated means for the brake band, substantially as described.
